UNITED STATES PATENT OFFICE.

ARTHUR T. HAGEN, OF ROCHESTER, NEW YORK, ASSIGNOR TO THE AMERICAN LAUNDRY MACHINERY COMPANY, OF CINCINNATI, OHIO, A CORPORATION OF OHIO.

VALVE MECHANISM FOR WASHING MACHINERY.

1,267,403.

Specification of Letters Patent. Patented May 28, 1918.

Application filed July 14, 1915. Serial No. 39,898.

To all whom it may concern:

Be it known that I, ARTHUR T. HAGEN, of Rochester, in the county of Monroe and State of New York, have invented certain 5 new and useful Improvements in Valve Mechanism for Washing Machinery; and I do hereby declare the following to be a full, clear, and exact description of the same, reference being had to the accompanying 10 drawings, forming a part of this specification, and to the reference numerals marked thereon.

The present invention has for its chief purpose to provide a valve mechanism applicable to liquid receptacles, such for example as are used in clothes washing machinery, embodying generally a movable container arranged within a liquid holder or receptacle, with provision for filling and emptying the 15 receptacle of its liquid contents at stated intervals. In a more specific aspect, the invention consists in simplifying the construction and operation of this class of devices generally and in correlating the inlet and 20 outlet valve mechanisms for the water so as to effect automatic control of the machine. A further purpose of the invention resides in the provision of an arrangement whereby a single operation is all that is required to 25 effect emptying the receptacle of its contents and subsequently filling it with fresh liquid to a predetermined point, such operation being dependent upon the opening of an outlet valve which permits the discharge of the 30 contents of the receptacle and results in the subsequent closing of said valve and opening of an inlet valve that effects filling of the receptacle up to a predetermined level after which the inlet valve is automatically closed. 35 To these and other ends the invention consists in certain improvements and combinations of parts all as will be hereinafter more fully described, the novel features being pointed out in the claims at the end of the 40 specification.

In the drawings:

Figure 1 is an end elevation of a washing machine having applied thereto a preferred arrangement according to my invention and 45 showing the outlet valve closed and the inlet valve open, in the act of filling the receptacle;

Fig. 2 is a similar view, partially broken away, showing the outlet valve open, in the act of emptying the receptacle and the inlet 55 valve closed;

Fig. 3 is an enlarged view of the valve operating mechanism, showing the parts in normal position, the inlet and outlet valves being both closed and the receptacle filled; 60

Fig. 4 is a similar view showing the position of the parts assumed when the outlet valve is closed and the inlet valve is open in filling the receptacle, corresponding to Fig. 1; 65

Fig. 5 is a similar view showing the position of the parts assumed when the outlet valve is open and the inlet valve closed for emptying the receptacle, corresponding to Fig. 2; 70

Fig. 6 is a plan view of the valve operating mechanism;

Fig. 7 is a front elevation of the same;

Fig. 8 is an enlarged sectional view with parts in elevation of one of the inlet valves 75 and supplemental valve controlling it, in the position of filling the receptacle;

Fig. 9 is a vertical sectional view through the inlet valve casing;

Fig. 10 is a vertical sectional view through 80 the inlet valve casing, showing one of the valves;

Fig. 11 is a detail sectional view of the supplemental valves and casing, and

Fig. 12 is a detail view showing one of the 85 actuators for the corresponding valve controller in its inoperative position.

Similar reference characters throughout the several views indicate the same parts.

The invention is applicable to different 90 types of machines and embodies generally inlet and outlet valves connected to a liquid receptacle and forming the means for supplying liquid to and discharging it from the receptacle, together with provision for 95 manually operating the outlet valve to empty the receptacle. Mechanism is provided for determining the operation of the inlet valve, and is connected to the operating means for the outlet valve in such a manner as to effect closing of the outlet valve when the receptacle is emptied of its contents and thereafter to automatically open the inlet valve, the closing of which is sub- 100

sequently determined when the level of water in the receptacle reaches a predetermined point.

In the present arrangement, I have shown 5 the improvements in their application to a clothes washing machine of standard type, such as embodies a receptacle 1, having supporting legs 2, and mounted on a concrete or other foundation 3, having a gutter 4 10 to carry off the liquid when discharged from the receptacle. 5 designates the inlet pipe leading from the valve casing 6 to which are connected hot and cold liquid supply pipes 7, from which the receptacle is furnished 15 through the inlet pipe 5 according to the position of the inlet valves 8. The inlet valves 8 for hot and cold water are both constructed and operated in the same manner and for convenience in the present application, I will describe only one of these.

Each valve 8 is of the balanced pressure type and to this end carries a piston 9 movable in a chamber 10 while the fluid pressure has access to the upper side of the 25 piston through the passage 11 shown in Fig. 10. Thus when the pressure is the same on the upper and lower faces of piston 9, as shown in Fig. 10, the valve is held closed and in order to open the latter, pressure on 30 the upper side of the piston is relieved. To this end, the chamber 10 connects with a pipe 12 leading to a supplemental valve chamber 13 in which is arranged a supplemental valve 14 coöperating with a seat 15 and carrying a valve stem 16 extending 35 downwardly beyond the casing as shown in Fig. 8. The casing 13 also includes a passage 17 connecting with the two ports controlled by the valves 15, and the passage 40 17 leads to a discharge or outlet 18. Thus when the supplemental valves 15 are open, pressure is released from the upper side of the pistons 9 so that the greater pressure on the under side of the piston elevates them 45 and opens the valves 8 to admit water to the receptacle, and I will now describe the means for controlling the position of the supplemental valves 15.

19 is a bracket mounted on the valve casing 6 and arranged on this bracket is a controller for each supplemental valve 15 which preferably comprises a body portion 20 pivoted about the axis 21 and having a nose 22 extending into the path of an actuator 55 to be described presently. The controller also includes an extension 23 for engagement with the valve stem and an arm 24 projecting into the path of a liquid controlled member to be described presently. 60 Also arranged on the bracket 19 is a carrier pivoted at 25 and embodying upstanding arms 26 on which are movably mounted the weighted actuators 27, each one arranged to coöperate, when in operative position, with

the corresponding supplemental valve controller by engagement with its nose 22. When the carrier is moved from the position shown in Fig. 5 to that shown in Fig. 4, the actuators 27 engage the noses 22 on the controllers, moving the supplemental valves 70 to the position in Fig. 8. If it is desired to supply only hot or cold water, the corresponding actuator 27 may be swung to its inoperative position shown in Fig. 12 when it will pass the corresponding valve controller without engaging the nose 22 and thus permit the supplemental valve and the corresponding inlet valve to remain closed. The carrier is provided with an arm 28 which is pivotally associated with a connecting rod 29, in turn connected to a lever 30 carrying a treadle 31. 32 is the receptacle outlet in which is arranged the valve 33 having a stem 34 in the path of the tail piece 35 on the lever 30. When it is desired to open the outlet valve, the treadle 31 is depressed moving the connecting rod 29 downwardly at the same time, as shown in Figs. 2 and 5. The outlet valve is held open by means of a weighted lever 35^a pivoted at 36 on an arm 37, and carrying an extension 38 provided with a roller 39 which engages the upper end of the connecting rod 29 in the manner shown in Fig. 5. The lever 35^a is weighted at 40, to hold it in locking engagement with the rod 29 and also carries an arm 41, by which it is moved out of locking position when the receptacle is empty, whereupon the weight 42 returns the lever 30 to its normal position permitting the outlet valve to close by gravity, and at the same time the carrier moves so as to operate the controllers and open the supplemental valves as shown in Fig. 4, to permit the receptacle to fill. I will now describe the liquid controlled means whereby the operation just described is effected when the receptacle is emptied, and the inlet valves are closed when the receptacle is filled.

43 designates a float chamber connected with the receptacle by the pipe 44 and 45 is a float movable in the chamber 43 and carrying the vertically extending guide 46 having a flange 47 at its upper end arranged for engagement with the arm 41 as shown in Fig. 5. Adjustably arranged on the guide 46 is a pair of stops 48 provided with spring actuated clutches 49 for holding them in adjusted position. The stops 48 are arranged for engagement with the arms 24 on the valve controllers as the guide is moved upwardly, in order to move the controllers from the position shown in Figs. 1, 4 and 8 to that shown in Figs. 2, 3 and 5, permitting the supplemental valves and the inlet valves to close and thus cutting off the supply of fresh liquid to the receptacle, and

by changing the position of the stops 48 on the guide, the time of closing the inlet valves can be adjusted to determine the proportion of cold and hot water that is supplied to the receptacle.

The operation of the structure is briefly as follows: Assuming the parts to be in the position shown in Fig. 3, the guide 46 is in its uppermost position, the receptacle is filled to the normal level, and the valves are all closed. When it is desired to empty the receptacle, treadle 31 is engaged and forced downwardly, elevating outlet valve 33 and lowering connecting rod 29 until the parts assume the positions shown in Figs. 2 and 5, where the extension 38 on lever 35^a engages the upper end of connecting rod 29, holding it lowered, and the carrier has been moved on its pivot until the actuators 27 are carried past the noses 22 on the valve controllers, as shown clearly in Fig. 5. As the liquid is discharged from the receptacle, float 45 is lowered in the float chamber, causing the guide 46 to move downwardly, at which time the flange 47 engages the arm 41 on lever 35^a, and as the float reaches the limit of its downward movement, the lever 35^a is rocked about its axis far enough to release the rod 29 permitting the latter to return to its normal position as in Figs. 1, 3 and 4. This operation also forces the actuators 27 laterally until they engage the noses 22 on the valve controllers, moving the latter to the positions shown in Figs. 1, 4 and 8, and opening the supplemental valves. This releases pressure on the upper side of the pistons 9 and permits the inlet valves to open, letting in a supply of fresh water, the proportion of hot and cold being varied to suit the demands of the machine by adjusting the stops 48. If only hot or cold water is desired, the corresponding actuator 27 is moved to its inoperative position so that the corresponding inlet valve remains closed. As the receptacle is filled, the float 45 again rises in its chamber until the stops 48 engage the arms 24 on the valve controllers, moving the latter from the position shown in Fig. 8 to that shown in Figs. 3 and 5, and thus closing the inlet valves. The parts are then in the position appearing in Fig. 3 and ready for another operation.

The particular construction that I have described is not to be considered as the only means for accomplishing the purposes of my improvement and it will be understood that the present application is intended to cover any modifications or departures coming within the spirit and purpose of the invention as set forth in the claims.

I claim as my invention:

1. The combination with a liquid receptacle, of inlet and outlet valves, a controlling device which opens the outlet valve, and is

automatically held in position to retain said valve open, and means controlled by the liquid in the receptacle and actuated through the controlling device, operating to open the inlet valve when the outlet valve is automatically closed after emptying the receptacle.

2. The combination with a liquid receptacle, of inlet and outlet valves, a controlling device for the outlet valve, means actuated by the controlling device and operating to automatically close the inlet valve when the receptacle is filled and to automatically open the inlet valve and close the outlet valve when the receptacle is emptied.

3. The combination with a liquid receptacle, of inlet and outlet valves, and means controlled by the liquid in the receptacle acting automatically to open the inlet valve and close the outlet valve when the receptacle is emptied, and to close the inlet valve when the outlet valve is opened.

4. The combination with a liquid receptacle, of inlet and outlet valves, a controller for the inlet valve, a pivoted carrier movable independently of the controller, an actuator mounted on the carrier and coöperating with the controller, operative connections between said carrier and the outlet valve, and means acting automatically to hold the outlet valve open until the receptacle is empty.

5. The combination with a liquid receptacle, of inlet and outlet valves, a supplemental valve governing the positions of the inlet valve, a controller for said supplemental valve, a movable carrier, an actuator movably mounted on the carrier and adjustable into or out of coöperative relation with the controller, and operative connections between said carrier and the outlet valve.

6. The combination with a liquid receptacle, of inlet and outlet valves, a supplemental valve for governing the position of the inlet valve, a controller for the supplemental valve, a movable carrier, an actuator mounted on the carrier and coöperating with the controller, and operative connections between the carrier and outlet valve whereby the controller for the supplemental valve is moved by the actuator to open the inlet valve when the outlet valve is closed, and means controlled by the liquid in the receptacle to move the controller and close the inlet valve when the receptacle is filled.

7. The combination with a liquid receptacle, of inlet and outlet valves, a controller for the inlet valve, a pivoted actuator for the controller, said actuator and controller being relatively movable into operative and inoperative relationship, operative connections between the actuator and outlet valve and means acting automatically to hold the outlet valve open until the receptacle is empty.

8. The combination with a liquid receptacle, of inlet and outlet valves, a controller for the inlet valve, an actuator for the controller, means connecting the actuator and outlet valve whereby the actuator moves the controller to open the inlet valve when the outlet valve is closed, and means controlled by the liquid in the receptacle for closing

the outlet valve when the receptacle is empty and for moving the controller to close the inlet valve when the receptacle is filled.

ARTHUR T. HAGEN.
